CLAIM

The ornamental design for an ear piercing cartridge, as shown and described.

DESCRIPTION

FIG. 1 is a perspective view of the ear piercing cartridge in accordance with the present invention;

FIG. 2 is a top plan view of the ear piercing cartridge;

FIG. 3 is a front elevational view of the ear piercing cartridge;

FIG. 4 is a side elevational view of the ear piercing cartridge, the two side views being symmetrical;

FIG. 5 is a rear elevational view of the ear piercing cartridge; and,

FIG. 6 is a bottom plan view of the ear piercing cartridge. The broken line showing in FIG. 1 is for illustrative purposes only and forms no part of the claimed design.
